His Attorney

UNITED STATES PATENT OFFICE.

PAUL M. CONRAD, OF ALCOA, TENNESSEE, ASSIGNOR TO GENERAL ELECTRIC COMPANY, A CORPORATION OF NEW YORK.

ELECTRORESPONSIVE DEVICE.

Application filed February 27, 1926. Serial No. 91,211.

My invention relates to electroresponsive devices such for example as relays and particularly to devices of this character which are operated by a varying or alternating electric current. The object of my invention is to secure in devices of this character a pick up and release at current values which are not greatly different, in other words a close range operation, and to secure also an accelerating or snappy action of the movable member of the device as distinguished from a uniform or drifting action. A further object is to secure such an operation in efficient and practical apparatus.

To accomplish these objects, I provide means for impressing upon a movable member a force which remains relatively constant throughout the movement of said member during any given condition of the actuating current, and I also provide means for impressing upon the movable member another force which increases or decreases throughout the movement of said movable member during any given condition of the actuating current. These two forces are given such absolute and relative values as is desired by suitably proportioning or adjusting the different elements of the device. I have also devised efficient and practical apparatus for generating and applying these forces.

The following specification and the accompanying drawing disclose in detail one specific embodiment of my invention. Referring to the drawing, Fig. 1 is a side view of said relay; and Fig. 2 shows this relay associated with switches and circuits for changing the operation of a motor from forward to reverse and vice versa, with fluctuations of voltage in an alternating current line, and for maintaining the motor at rest for a certain intermediate voltage.

Referring to Fig. 1, an actuating electromagnet 1 having a coil 1^a and a core 2 acts upon a movable member 3 to cause a movable contact 14 to engage a fixed contact, such as the contact 16, for certain conditions of the current in the actuating coil 1^a of the magnet 1, and to remain disengaged therefrom during other conditions of the current in this coil. The movable member 3 is

ordinarily a lever. In the specific embodiment here illustrated it has three arms 5, 6 and 7 radiating from the fulcrum 4. A mass of conducting material 8 is mounted on the movable member 3 adjacent one end of the coil 1^a so as to provide a closed conducting path for currents induced therein in response to variations or alterations of current in the coil 1^a. This mass of conducting material 8 is here shown as a closed ring mounted on the arm 5 and loosely encircling an extending end of the core 2. In the relay shown, this closed conducting path 8 is made of non-magnetic material such as copper or aluminum. A mass 9 of magnetic material of low retentivity such as soft iron or soft steel is also mounted on the movable member 3, and adjacent a pole of the electromagnet 1. This mass of magnetic material 9 is here shown as a plate carried on a bar 6 depending from one end of the arm 6, so that the plate 9 is near the other end of the core from that which is encircled by the closed conducting path 8. A contact 14 is carried by the movable member 3 for cooperation with one or more fixed contacts such as the contacts 15 and 16. In the construction shown a varying or alternating current in the coil 1^a generates forces which act upon the ring 8 and plate 9 and tend to rotate the movable member 3 in a clockwise direction. This tendency is opposed by a force or forces which act upon the movable member 3 and tends to move it in a counterclockwise direction. A spring may be used to provide this opposing force such as the spring 10 secured at one end to the arm 7 and at its other end to the nut 11. The nut 11 as shown is adjustable in the sleeve 12 by means of the thumb screw 13.

The device shown in Fig. 1 may be used either as a single or as a double contact relay. When used as a double contact relay, the spring 10 is adjusted to hold the movable contact 14 about half way between the fixed contacts 15 and 16 when the strength of the current in the coil 1 is about half way between that strength at which the contact 14 is desired to engage the contact 15 and that strength at which the contact 14 is desired to engage the contact 16. As long

as the current in the coil 1 remains at this strength, the lever 3 remains at rest and the contact 14 maintains its position apart from each of the contacts 15 and 16. If the current in the coil 1^a decreases when the contact 14 is in its intermediate position, the repulsion of the ring 8 and the attraction of the plate 9 decrease and the spring 10 rotates the lever 3 until contact 14 engages contact 15. If the current in the coil 1^a increases when the contact 14 is in its intermediate position, the repulsion of the coil 8 and attraction of the plate 9 increase and the lever 3 is rotated against the tension of the spring 10 until the contact 14 engages contact 16. Reversely if the current in the coil 1 increases sufficiently when the contact 14 is in engagement with the contact 15 or decreases sufficiently when the contact 14 is in engagement with the contact 16 the contact 14 returns to its intermediate position. When used as a single contact device, either of the contacts 15 or 16 may be omitted or may be left disconnected from any circuit so that this contact will serve as a mere stop. The spring 10 may then be adjusted if desired so as just to seat the movable contact 14 against the disconnected contact when the current in the coil 1^a is at its critical value, that is at the value at which an action of the relay is desired.

In Fig. 2 the same relay is shown with its coil 1^a connected across a line 17 to close one or the other of the switches 18, 19, as the movable contact engages one of the other of the fixed contacts, and to send current from the line 20 to the motor 21 to cause the motor to advance or reverse as the voltage in the line 17 rises above or falls below a certain value, and to cause the motor to remain at rest while the voltage in the line 17 has this particular value.

The device hereinabove described, whether located in such a system as is shown in Fig. 2 or in any other of the many situations where alternating current relays and similar electroresponsive devices can be used, can be designed for close range operation and at the same time be given a certain degree of snappy or accelerating action, both in pick up and release. The intensity of the repulsion acting upon the coil 8 varies very decidedly with variation in the magnitude of the current in the coil 1, but it does not vary to any considerable extent with variations in the distance between the ring 8 and the coil 1. If the ring 8 were used alone, i. e. if the plate 9 were omitted, the difference between the pick up value of the current in the coil 1 and its release value would be very small indeed, the friction in the bearing 4 and the variation in the tension of the spring 10 being considered negligible. But this very close operation though theoretically desirable would be attended by a sluggishness in the movement of the contact 14 which is undesirable. The ring 8 would drift or move steadily to or from a contact engaging position whenever the current in the coil 1^a departed slightly from its critical value, where as accelerated motion is desired which gives a sharp click on engaging and a rapid separation on disengaging. The desired acceleration is obtained by the addition of the plate 9. The attraction between the core 2 and the plate 9 not only varies with the magnitude of the current in the coil 1, but it increases very decidedly as the distance between the core 2 and plate 9 is decreased and decreases very decidedly as the distance between these parts is increased. This increasing or decreasing attraction tends to produce an accelerated motion both in pick up and in release. If the plate 9 alone were used, i. e. if the ring 8 were omitted, a maximum effect of this kind would be secured, but this advantage would be attained by a sacrifice of close range operation. The force acting upon the plate 9 at the end of any movement thereof would be so much greater than the force acting at the beginning of that movement, as to require a considerable change in the current in the coil 1^a to initiate the reverse of that movement. By employing both the ring 8 and the plate 9, and properly proportioning their relative effectiveness a close range operation and an accelerating action can be secured at the same time. Where a very close range operation is more important than a very snappy engagement or disengagement, the plate 9 will be made small; or its distance from the core 2 made large, or the ring 8 will be made very highly conducting, or of larger cross section, or other means will be employed, to decrease the intensity of the attraction of the plate 9 relative to the repulsion of the ring 8. Vice versa where a snappier motion is desired and very close range is less important, the design will be reversed. And in general those skilled in the art will proportion the relative effect of the ring 8 and the plate 9 to secure that proportioning of closeness of range and snappiness of motion which they deem most desirable in the particular situation in which they expect the relay to be used.

It will be observed that the lever 3 has impressed thereon a force which in a general way is proportional to a resultant of the forces exerted by the electromagnet 1 on the ring 8 and plate 9; and that the repulsion of the coil 8 and attraction of the plate 9 by the electromagnet 1 vary with the intensity of an alternating current in the coil 1^a; and that the movable member 3 moves in response to variation in the forces between the electromagnet 1 and the closed conducting path 8 and mass of magnetic material 9, for certain values of these forces.

What I claim as new and desire to secure by Letters Patent of the United States is:

1. An electroresponsive device comprising an actuating coil, a movable member, means for impressing on said movable member a force which varies with the variation of the current in the actuating coil but does not vary substantially with the motion of the movable member, and means for impressing on said movable member another force which varies with the variation of the current in the actuating coil and which does substantially vary with the motion of said movable member.
2. An electroresponsive device comprising an actuating coil, a movable member, means for impressing on said movable member a force which varies with the variation of the current in the actuating coil but which does not vary substantially with the motion of the movable member, means for impressing on said movable member another force which varies with the variation of the current in the actuating coil and which does vary substantially with the motion of said movable member, and which is so directed as to aid the first mentioned force, and means whereby the motion of the movable member in response to said forces is opposed by a substantially constant force.
3. An alternating current electroresponsive device comprising an actuating electromagnet, a mass of conducting material adjacent one end of said magnet, a mass of low retentivity magnetic material adjacent a pole of said magnet, a movable member and means for impressing on said movable member forces which are proportional to a resultant of the forces which are exerted by said electromagnet on said mass of conducting material and on said mass of magnetic material.
4. An alternating current electroresponsive device comprising an actuating coil, a core projecting from said coil at one end, a closed path conductor loosely surrounding the projecting end of said core, a mass of low retentivity magnetic material adjacent a pole of said core, and a member which moves in response to variation in the forces acting between said coil, core, conductor and mass of magnetic material for certain values of these forces.
5. A close range alternating current electroresponsive device comprising an actuating coil, a fixed core in said coil said core projecting at one end from said coil, a movable member, a closed path conductor carried by said movable member and surrounding said projecting end of said core, a mass of low retentivity magnetic material carried by said movable member adjacent the other end of said core, and means whereby a substantially constant force is exerted upon said movable member in opposition to the action of said coil and core upon said movable member, the action of said substantially constant force being equal to the action of said coil and core on said movable member for a certain intensity of alternating current in said coil.
6. An alternating current relay, comprising a lever, a closed path conductor of non-magnetic material carried by one arm of said lever, a piece of soft iron or soft steel mounted on another arm of said lever, an actuating coil, a fixed core in said coil, said core extending beyond said coil at one end and through said closed path conductor, the other end of said core being adjacent said piece of iron or steel, a movable contact carried by said lever, a fixed contact with which said movable contact cooperates, and a spring coating with said lever to hold the movable contact spaced from the movable contact when the intensity of the current in the actuating coil is below a certain value.
7. An electroresponsive device comprising a pivoted member having two arms, a closed path of non-magnetic conducting material upon one arm, a mass of low retentivity magnetic material upon the other arm, an actuating coil located between said arms and having a core, one end of which extends through the closed path of conducting material and the other end of which is near the mass of low retentivity magnetic material, a spring urging said pivoted member in a direction opposite to the direction in which it is urged by the action of the coil and core.
8. An electroresponsive device comprising a pivoted member having two arms, a closed path of nonmagnetic conducting material upon one arm, a mass of low retentivity magnetic material upon the other arm, an actuating coil located between said arms and having a core, one end of which extends through the closed path of conducting material and the other end of which is near the mass of low retentivity magnetic material, and a spring urging said pivoted member in a direction opposite to the direction in which it is urged by the action of the coil and core, the action of said spring being equal to the action of said core and coil for a certain predetermined intensity of alternating current in said coil.
9. An alternating current relay comprising a movable member, an actuating coil having a fixed core, a closed path of non-magnetic conducting material mounted on said movable member and surrounding one end of said core, a plate of low retentivity magnetic material mounted on said movable member adjacent the other end of said core, a spring urging the movable member in a direction opposite to the direction in which it is urged by the action of the coil and core on the closed path of conducting material

and the plate of magnetic material, a movable contact carried by said movable member, and two fixed contacts, one on each side of said movable contact, the spring holding the movable contact spaced from the fixed contacts for a given intensity of the current in the actuating coil and causing or permitting said movable contact to engage one or the other of the fixed contacts as the intensity of the current in said coil falls below or rises above said given intensity.

In witness whereof, I have hereunto set my hand this 23rd day of February, 1926.

PAUL M. CONRAD.

Certificate of Correction.

Patent No. 1,646,233.

Granted October 18, 1927, to

PAUL M. CONRAD.

It is hereby certified that error appears in the printed specification of the above-numbered patent requiring correction as follows: Page 1, line 59, for the word "alterations" read *alternations*; page 2, line 53, for the word "variation" read *variations*; same page, line 71, before the word "accelerated" insert the word *an*; and that the said Letters Patent should be read with these corrections therein that the same may conform to the record of the case in the Patent Office.

Signed and sealed this 6th day of December, A. D. 1927.

[SEAL.]

M. J. MOORE,
Acting Commissioner of Patents.
